UNITED STATES PATENT OFFICE

131,511

DESIGN FOR A PIN

Robert W. Jenkinson, New York, N. Y.

Application November 5, 1941, Serial No. 104,030

Term of patent 3½ years

To all whom it may concern:

Be it known that I, Robert W. Jenkinson, a former subject of Great Britain, who has foresworn his allegiance to Great Britain, and declared his intention of becoming a citizen of the United States, and is therefore not a citizen of any country at the present time, who is residing in New York, in the county of New York and State of New York, have invented a new, original, and ornamental Design for a Pin, of which the following is a specification, reference being had to the accompanying drawing, forming a part thereof.

Fig. 1 is a front view of the pin showing my new design;

Fig. 2 is a rear view, and

Fig. 3 is an edge view thereof.

I claim:

The ornamental design for the pin, as shown.

ROBERT W. JENKINSON.
